F. VAN D. LONGACRE

COMPRESSOR REGULATOR

Filed Feb. 5, 1926

Patented Aug. 3, 1926.

1,594,986

UNITED STATES PATENT OFFICE.

FREDERICK VAN DUZER LONGACRE, OF YONKERS, NEW YORK, ASSIGNOR TO INGER-SOLL-RAND COMPANY, OF JERSEY CITY, NEW JERSEY, A CORPORATION OF NEW JERSEY.

COMPRESSOR REGULATOR.

Application filed February 5, 1926. Serial No. 86,302.

This invention relates to compressor regulators for step by step control. The objects of the invention are to avoid the necessity of separate clearance valves for the compressor by making the compressor valves also perform the functions of clearance valves. In this way more space is available for compressor valves, heretofore occupied by the clearance valves, though clearance chambers also occupy less space and can be more compactly and conveniently arranged and the cost is cheapened.

Another object of the invention is to obviate the necessity of rendering any of the compressor valves inoperative when a clearance chamber is brought into communication with the cylinder, thus avoiding wear on the compressor valves. In my system the compressor valves continue to function as usual at all times.

Further objects of the invention will appear and the invention is shown in one of its preferred forms in the accompanying drawing, which is a diagrammatic view partly in longitudinal elevation of a compressor and clearance control applied both to the inlet and discharge valves, showing step by step regulation.

The compressor valves may be of any suitable type, but are shown in this instance like the valve covered by my United States Patent No. 1,550,376, granted August 28, 1925. The regulator for controlling the valves to obtain step by step unloading and loading is illustrated diagrammatically and may be like that covered by United States Patent No. 1,430,578, granted October 3, 1922 to C. W. Metzgar, to which I have permission to refer.

Referring to the drawings, the compressor cylinder A is here shown double acting and has the usual piston B driven from any suitable motor or engine (not shown). The invention is, however, obviously equally applicable to any compressor, pump or the like, whether single or double acting, simple, duplex or compound.

The inlet valves C and discharge valves D control the flow of pressure fluid to and from the compressor as usual from the inlet E, which forms part of the external inlet passage F, to the discharge outlet G, which forms part of the external discharge passage H, and it is to be understood that the word "external" defines the passages as external

to the cylinder compression space. The receiver G' is adapted to be connected to the discharge pipe G. The cylinder has the usual heads J and K, and is conveniently provided with the clearance chambers L, O, 60 P and Q, having means of communication with the cylinder through the respective openings R, S, T and U and the compressor valve openings V, W, X and Y in the cylinder walls as shown.

The inlet and discharge valves C and D are bodily movable or adjustable relatively to their respective valve openings V, W, X and Y, either by hand if desired but preferably by automatic fluid actuated means 70 shown as plungers a in chambers b, opposed by springs c, which chambers are adapted to be connected by pipes 1, 2, 3 and 4 to the automatic regulator casing d of the regulator Z, constructed and operating like that 75 shown in the Metzgar Patent No. 1,430,578 referred to.

A certain convenient portion or member of each compressor valve is arranged to control the clearance chamber openings and 80 take the place of independent clearance valves, and in this instance portions e of the valve seats are prolonged to form circular flanges cooperating with the clearance chamber openings R, S, T and U, to open and cut off said clearance chambers in accordance 85 with the movements or adjustments of the compressor valves in the cylinder openings.

When pressure is released behind one of the valve plungers a, the spring c lifts the 90 valve structure bodily from the cylinder opening, and at the same time places a clearance chamber in communication with the cylinder for a step of unloading, without 95 however, altering the function of the compressor valve, which continues to operate on its seat. More volume is added to the cylinder but the operation of the compressor valve is not affected. The compressor valves are constantly maintained operative and are 100 not rendered at any time inoperative, which is a distinct and important advantage since there is no interference with their action, multiplicity of parts is greatly reduced, but one set of valves is necessary, and replacement of valves is simplified.

The movable discharge valve structures are preferably guided as units in cages f formed separately from the caps or cover plates g and the bolts h clamp the valve 110

parts together. The springs *c* are held between the flanged heads *j* and the cages *f*, while the plungers *a* are separate members. The parts are packed as shown at those 5 points at which leakage might occur.

The inlet valve structures are substantially like the discharge valve structures, except as to the shape and form of the cages *k* which form guides, and the covers *o*, but the 10 functions of the corresponding parts are the same.

The regulator *Z* comprises a casing *p* connected by a pipe *q* to the receiver and a branch pipe supplies receiver pressure to the 15 case *d* adapted to contain the valve mechanism which automatically and successively supplies pressure fluid to the pipes 1, 2, 3 and 4 leading to the compressor valve operating plungers to maintain the valve structures in normal inwardly seated positions, or opens said pipes successively to atmosphere. The lever *r* pivoted at *s* is actuated by the pin *t* in accordance with variations 20 in receiver pressure above a predetermined minimum, and the valve stem *u* of a pilot or auxiliary valve pivotally hung on said lever *r* controls the operation of the regulator. The movement of the lever *r* is limited by the stops *v* and *w* and checked by the 25 spring *x*, all as shown in the aforesaid Metzgar Patent No. 1,430,578.

In the operation of the apparatus, let it be assumed that all the compressor valve structures are adjusted inwardly and seated 35 on their seats in the cylinder openings, so that the compressor is running under full load. All the pipes 1, 2, 3 and 4 are supplied with receiver pressure and the plungers *a* of the compressor valves are forced 40 inwardly in the chambers or cylinders *b*.

In the position of the parts shown in the figure, one compressor discharge valve *D*, and its parts, has been raised from its seat in the opening *V* for the first step of 45 unloading, indicating that there has been an increase of receiver pressure sufficient to cause the regulator *Z* to operate. The lever *r* has been raised a given distance by receiver pressure and the pipe 1 has been 50 opened to atmosphere so that plunger *a* of said discharge valve *D* has been relieved of pressure and the spring *c* has retracted the compressor valve as shown, thus opening the clearance chamber *L* and reducing the 55 compressor load one quarter. The successive steps occur in the same manner to unload and load the compressor.

What I claim is:—

1. In a compressor, the combination of a 60 cylinder and piston, a fluid passage external to the cylinder, a clearance chamber,

both being adapted to communicate with the cylinder, and a compressor valve controlling said means of communication of both the external passage and clearance chamber 65 with the cylinder.

2. In a compressor, the combination of a cylinder and piston, a fluid passage external to the cylinder, a clearance chamber, both having means of communication with the 70 cylinder, a compressor valve controlling communication between the said external passage and the cylinder, and means forming a part of said valve controlling communication between the clearance chamber 75 and the cylinder.

3. In a compressor, the combination of a cylinder and piston, a fluid passage external to the cylinder, a clearance chamber, both being adapted to communicate with the cylinder, and a compressor valve controlling said means of communication of both the external passage and clearance chamber with the cylinder while maintaining the compressor 80 valve at all times operative.

4. In a compressor, the combination of a cylinder and piston, a fluid passage external to the cylinder, a clearance chamber, both having means of communication with the cylinder, a compressor valve controlling communication between the said external passage and the cylinder, and means forming a part of said valve controlling communication between the clearance chamber and the cylinder without rendering the compressor 90 valve at any time inoperative.

5. In a compressor, the combination of a cylinder and piston, a clearance chamber, a constantly operative compressor valve, and an adjustable valve member for the 100 compressor valve controlling the clearance chamber, whereby adjustment of the said valve member unloads the compressor without rendering the compressor valve inoperative.

6. In a variable volume compressor, the combination of clearance chambers, and compressor valves controlling both the flow of fluid and the said clearance chambers, for unloading and loading the compressor step 110 by step.

7. In a variable volume compressor, the combination of clearance chambers, and compressor valves controlling both the flow of fluid and the said clearance chambers, for unloading and loading the compressor step by step without rendering the compressor valves inoperative.

In testimony whereof I have signed this specification.

FREDERICK VAN DUZER LONGACRE.
